(57) **CLAIM**

The ornamental design for a pair of tool handles, as shown and described.

DESCRIPTION

FIG. 1 is a front elevational view of a pair of tool handles according to the concepts of the present invention;

FIG. 2 is a rear elevational view thereof;

FIG. 3 is a bottom elevational view thereof;

FIG. 4 is a top elevational view thereof;

FIG. 5 is a front elevational view of an alternate embodiment of the pair of tool handles according to the concepts of the present invention;

FIG. 6 is a rear elevational view thereof;

FIG. 7 is a bottom elevational view thereof; and,

FIG. 8 is a top elevational view thereof.

In the above described drawings, portions of the tool handles shown in ghost lines form no part of the claimed invention.
